UNITED STATES PATENT OFFICE

CHARLES H. BAKER, OF HUDSON, MASSACHUSETTS, ASSIGNOR TO FIRESTONE FOOT-WEAR COMPANY, OF HUDSON, MASSACHUSETTS, A CORPORATION OF MASSACHUSETTS

SEPARABLE FASTENER

Application filed October 27, 1926. Serial No. 144,473.

This invention relates to separable fasteners of the type in which a plurality of mating and interlocking fastening elements are arranged along opposite edges of a closure, being brought together into interlocking condition by means of a movable slider or cam member which opens or closes the fastener as the slider is moved up or down along the closure.

The purpose of the present invention is to improve upon the slider construction so that it will be strengthened and reenforced in such a manner as to prevent spreading of the plates which constitute the body of the slider. Heretofore various expedients have been suggested and used for the purpose of eliminating any spreading action of the slider, which results in faulty operation of the fastening elements. The present invention has for its object the provision of a new and improved slider construction which will give greater strength and resistance to spreading than prior forms. The results are obtained in an inexpensive and neat appearing construction which it is the purpose of the present application to cover, changes and modifications being possible within the scope of the invention as set forth in the claims.

In the drawings, in which the preferred form of the invention is shown:

Figure 1 is a front view of a closure with my new and improved form of slider thereon;

Figure 2 is a side view partly in section; and

Figure 3 is a section on the line 3—3 of Figure 1.

The closure consists of a series of interlocking and mating elements which are secured to the edges of the opening, as illustrated in Figure 1, in which a row of male elements is indicated by the numeral 5 and a row of female elements by the numeral 6, the elements being brought into mating and interlocking engagement by the slider as is usual. The particular design of the interlocking elements is not essential to some aspects of the present invention, which is directed more especially to the construction of the slider.

The slider is composed of two plates 7 and

8 placed one above the other, the plates being flanged along their outer edges with the flanges projecting toward one another, as shown at 10. The slider is formed with two diverging channels 12 and 13 for the male 55 and female members which merge into the single channel 14 through which the connected fastener issues, the aforementioned flanges guiding the slider over the interlocking elements.

The upper portion of the plates are depressed to form triangular flat areas 18 which are placed in contact with one another and thereby space the wings throughout the channels. The areas at this point are extended 60 upwardly beyond the main body of the slider, to afford a greater area of contact between the plates. The apex 19 of the triangular area is directed downwardly toward the channel 14 and operates as the spreader for 65 separating the closures, it being observed that adjacent the apex and along the walls of the triangular spreader portion the channel 12, for the male members 5, is restricted somewhat, as shown at 20, for guiding the 70 prongs of the male members so that they will properly enter the female members of the fastener.

The depressed triangular areas 18 between the channels 12 and 13 serve not only as a 75 spreader or divider for the separable fastener, but also as a means for connecting the two plates which form the upper and lower plates of the slider, by means of a staple 25, the ends of which may be reduced to form shoulders 26 bearing against the upper plate. The ends 27 of the staple are passed through the plates and riveted over to securely fasten the two plates together, a backing plate 28 being placed against the rear plate 8 more firmly 80 to secure the rivet in place. By the provision of the stapled rivet as shown, the two plates are securely fastened and braced by the two points of attachment which serve to prevent any rocking movement between the two 85 plates. The upper edges of the triangular area of each plate are formed with a flange 31 extending from channel to channel, which flange operates as a further reenforcement 90 or brace for the plates constituting the slider. 100

The open head of the rivet is used as a keeper for the operating tab 30 for the slider which is loosely pivoted thereon.

It will be observed that a very strong and economical construction of slider has been devised, and one which is easy and inexpensive to manufacture and assemble. The stapled rivet and the large area of contact between the two plates of the slider effectually prevent spreading between the plates and at the channels. The triangular depressed areas on the slider also afford an easy means of obtaining the pointed spreader which separates the male and female members of the separable fastener. Other objects and advantages will be apparent from the description of the device, as will be understood and appreciated by those skilled in the art. The plates are formed by usual stamping operations and are therefore economical of manufacture.

What is claimed is:

1. A separable fastener comprising interlocking members secured to the edges of a closure, and a slider to operate the closure, said slider comprising independent spaced plates forming channels for the passage of the members, depressed areas in the upper portions of said plates which areas are placed in contact, fastening means to secure the two plates together passing through the areas, and reinforcing flanges about the upper margins of the areas.

2. In a separable fastener, a slider comprising two metal plates of substantially even thickness throughout, depressed areas in said plates which are in contact and thereby space the balance of the plates to form channels, the channel at one side of the depressed area comprising an enlarged and reduced opening leading one into the other in combination with mating interlocking fasteners including male members which are guided by the reduced channel, and flanges formed about the upper sides of the depressed areas.

3. In a separable fastener, a slider comprising two metal plates having depressed areas in contact, the remainder of the plates affording channels for the passage of the members of the fastener, flanges formed about the upper sides of the depressed areas, and a rivet passing through the areas.

4. In a separable fastener, a slider comprising two metal plates having depressed triangular areas in contact, the remainder of the plates affording channels for the passage of the members of the fastener, a backing plate seated in one of the depressed areas, and a stapled rivet passing through the areas and through the backing plate for retaining an operating tab.
